UNITED STATES PATENT OFFICE.

HENRY O. JACKSON, OF DENVER, COLORADO, ASSIGNOR TO THE JACKSON COMPRESSOR COMPANY, OF DENVER, COLORADO, A CORPORATION OF COLORADO.

ROTARY AIR-COMPRESSOR.

1,352,751.

Specification of Letters Patent. Patented Sept. 14, 1920.

Application filed June 19, 1919. Serial No. 305,312.

To all whom it may concern:

Be it known that I, HENRY O. JACKSON, a citizen of the United States, residing at the city and county of Denver and State of Colorado, have invented certain new and useful Improvements in Rotary Air-Compressors; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in rotary air compressors or pumps, and while the structure will be described particularly with reference to its employment as an air compressor, it must be understood that it 20 may be employed for pumping fluids other than air.

My object is to provide a construction of this class, which shall efficiently and economically perform the air-compression or 25 pumping function.

Generally speaking, the machine consists of a casing having an approximately cylindrical chamber, in which is eccentrically mounted a rotor, carrying radially-disposed, 30 slidable blades which, when the machine is in operation, are held outwardly in contact with the interior surface of the chamber by centrifugal force. Preferably I employ springs acting on the inner extremities of 35 these blades, whereby they are normally held at their outward limit of movement, even when the machine is not in use.

Arranged below the casing is a lubricant chamber, from which the oil is drawn into 40 the center of the rotor and caused to flow outwardly around the blades for lubrication and sealing purposes by the centrifugal force developed by the rotor.

This lubricating feature is very important 45 and necessitates a separator in which the compressed air is separated from the oil, the latter being returned to the lubricant receptacle whereby a circulation of oil from the lubricant receptacle through the rotor 50 chamber and thence through the separator and back to the receptacle is constantly maintained when the apparatus is in use. Hence, it will be observed that the separator is an exceedingly important feature of my 55 improved construction.

This separator is arranged at one side of the casing carrying the rotor and is in communication with the rotor chamber through the medium of ports controlled by check valves. The separator consists of a casing 60 which is approximately rectangular in shape, both in horizontal and vertical section, and its interior is provided with a central member dividing the chamber of the separator into two compartments, the walls 65 of this central member, as well as the opposing walls on opposite sides thereof being grooved to form V-shaped ribs whereby the contact surface for oil and air is relatively great. Within the spaces between the central member and the opposing walls are located baffles, whose function is to break up the air and oil during their passage through the separator, and facilitate the bringing of these fluids into contact with the ribbed 70 surfaces of the interior of the separator, the latter being so constructed that there is a constant circulation of cooling water, both to the central member and the outer walls thereof, whereby the ribbed surfaces 75 are kept constantly cool, which greatly facilitates the separation of the air from the oil and at the same time cools the air before it passes to the receiver.

It must be understood that when the machine is in operation, the oil or liquid lubricant within the receptacle is under the same pressure as the air within the rotor, and the separator; hence provision is made whereby this pressure is automatically relieved as soon as the rotor stops, otherwise the oil within the receptacle would continue to enter the rotor chamber and flood the structure.

Having briefly outlined my improvement, 95 I will proceed to describe the same in detail, reference being made to the accompanying drawing, in which is illustrated an embodiment thereof. In this drawing:

Fig. 1 is a side elevation of the machine, viewed from the side opposite that where the separator is located.

Fig. 2 is an end elevation of the same, or a view looking in the direction of arrow 2, Fig. 1.

Fig. 3 is a vertical, longitudinal section taken approximately on the line 3—3, Fig. 2.

Fig. 4 is a cross section taken approximately on the line 4—4, Fig. 3, looking toward the right.

Fig. 5 is a section taken through the valve mechanism located between the rotor chamber and the separator, shown on a larger scale than in the other views.

5 Figs. 6 and 7 are cross sections taken through the casing of the valve mechanism shown in Fig. 5, and on a larger scale.

10 Fig. 8 illustrates the several parts of one of the valves, shown on the same scale as in Fig. 5, but on a smaller scale than in Figs. 6 and 7.

15 Fig. 9 is a sectional detail view of the structure for automatically relieving the lubricant receptacle from pressure when the machine is not in use, the same being shown on a larger scale than in Fig. 2.

20 Fig. 10 is a detail view, partly in section, of one of the radial blades of the rotor, shown on a somewhat larger scale.

25 Fig. 11 is an end elevation of the same. The same reference characters indicate the same parts in all the views.

Let the numeral 5 designate a casing provided with a chamber 6 approximately cylindrical in shape and in which is eccentrically mounted a rotor, 7, the wall of the chamber conforming to arcs struck from a number of different radii, whereby the cylindrical rotor engages about one-quarter of the interior surface thereof. The rotor is journaled in the opposite heads 8 and 9 of the casing, one of the journals 10 being extended to form an exterior shaft 12, carrying a fly-wheel 13, the end of the shaft being further journaled in a support 14. The other journal 15 is centrally bored, as shown at 16, and communicates at one extremity with a central cavity 17 in the rotor and at its opposite extremity with one end of a pipe 18, the opposite end of the pipe communicating with the bottom of an oil receptacle 19, by way of a passage 20. The flow of oil from the lubricant receptacle through the pipe 18 is controlled by a valve or cut-off 2 of any suitable construction.

The rotor is radially slotted as shown at 21 to receive blades 22 which, when the machine is in operation, are held outwardly in contact with the adjacent surface of the wall of the chamber by centrifugal force. Light springs 23 are seated in the slots 21 whose inner extremities are shouldered for the purpose, the said springs acting on the blades to normally hold them at their outward limit of movement, even when the machine is not in use.

60 The crescent-shaped space within the rotor chamber outside of the rotor is in communication with the atmosphere through an opening 100, and the chamber is slightly cut away or enlarged as shown at 24, where the air enters. This air is acted on by the blades and finally, when under maximum compression, it is forced out of the rotor chamber at the 65 opposite extremity of the crescent-shaped

space from where it entered, and passes thence through openings 25 formed in the casing, and thence into contact with cylindrical plungers 27, of the valve mechanism (see Figs 5 to 8). These plungers are normally acted on by springs 28, to cut off communication between the rotor chamber and the chamber 29 of the separator 30. The springs 28 surround reduced necks 31, formed on plugs 32, threaded into a core 33, positioned in a cylindrical cavity 34, bored in the wall of the rotor casing. When the plungers 27 are acted on by the air under pressure, they move outwardly or toward the separator and allow the air to enter a chamber 35 formed in the core 33, whence the air passes through openings 36 to a main opening 37, whence it passes through a central opening 38 formed in the adjacent wall of the separator.

85 This separator is composed of three distinct parts, consisting of exterior members 39 and 40, and a central member 41, the several members being connected by suitable fastening devices 42. The inner surfaces 90 of the two members 39 and 40 are constructed to provide a relatively large surface area. The inner portion 45 of the central member 41 is spaced from the walls of the other members and its surfaces opposite the surfaces 95 of the said members are also constructed to provide relatively large surfaces into contact with which the oil and air are brought for separating purposes. After leaving the separator the air escapes into a sleeve 59, 100 which is connected with a conduit 60, leading to the receiver (not shown). Furthermore, this sleeve 59 is threaded into the separator, as shown at 61, its opposite extremity having a threaded opening 62, in 105 which is inserted a screw plug 63. In the end of the sleeve nearer the separator is located a plunger valve 64, which is normally held in the closed position by a spring 65, one end of which engages the plug 63 while the other acts upon the valve. When the machine is in use and the compressed air is passing through the sleeve to the receiver, the valve 64 is open or unseated. Connected 115 with this valve, which is formed hollow for the purpose, is one end of a stem 66, whose opposite end is formed into a valve-piece 67, which engages a seat 68, formed around the inner extremity of a port 69, communicating with the atmosphere, this valve piece being 120 seated when the machine is in use to prevent the escape of fluid through the port 69, its stem being acted on by a spring 70, which is inclosed within a hollow part 71 of the plunger valve 64, the stem having an enlarged 125 head 72, which is acted on by the spring to hold the valvepiece 67 in such position that when the plunger valve is opened due to the passage of compressed air, the valve 67 will be seated. When, however, the machine is 13

not in use, the plunger valve 64 is moved to the closed position, thus opening the valve-piece 67. The port 69 is formed in a part 73, which is connected with the plug 63 by 5 a nut 74. Furthermore, the part 73 has a threaded opening 75, with which is connected one extremity of a pipe 76, whose opposite extremity is in communication with the top of the oil receptacle as shown at 77. Hence, 10 when the machine is not in use, the top of the lubricant receptacle is in communication with the atmosphere through the pipe 76, and the part 73, thus relieving the oil receptacle from pressure and preventing the flooding 15 of the structure with oil when the machine is not in use, or as soon as the rotor stops. During the circulation of the air and oil through the separator, the oil is separated from the air largely due to the cooling action 20 of the surfaces of the structure with which it is advantageously brought into contact, as heretofore explained, and passes downwardly through an opening 78 (see Fig. 4) into a conduit 79 and thence into the lubricant receptacle 19. Hence the oil is continually circulated through the machine when in use, being used over and over again, as will be readily understood, as there is no waste, or practically none. The interior surfaces 25 of the separator are kept cold by water circulation, which enters the separator through an inlet 80 at the bottom thereof, part of it passing through the spaces 81 in the outer members of the separator and 30 through the central space 82 of the member 41. The water, which passes upwardly through the separator, escapes through an outlet 83 to a pipe 84, which communicates, as shown at 85, with passages 86 in the wall 35 of the rotor casing. Again, another portion of the water which enters the separator passes by way of a conduit 87, into the lower portion of the water jacket part of the rotor casing. In this way, the entire structure 40 is kept cool at all times when in use. The pipe 84 is provided with an outlet 184 for the cooling water.

In order to facilitate the proper circulation of the fluid through the machine, as 50 heretofore described, a tube 88 has an open extremity 89 arranged in the passage between the rotor chamber and the separator, this extremity being elbow shaped and pointing toward the separator, the opposite extremity of 55 the tube being connected with the lubricant receptacle above the oil therein, as shown at 90. As the compressed air rushes past the extremity 89 of this tube, a slight vacuum is formed which acts upon the lubricant chamber 60 through the tube to facilitate fluid circulation, as heretofore described. The lubricant chamber is provided with an opening 91, with which a filling device 92 is connected, the upper extremity of this device having 65 a funnel 93, the passage of oil being regu-

lated by a valve 94. This tube 88 may be called a Pitot tube, reversed or positioned with its open extremity away from, rather than toward, the current.

In further explanation of the structure 70 shown in Fig. 9, attention is called to the fact that the sleeve 59 is provided with a bulb 95, which extends downwardly on the opposite side of the sleeve from the outlet 96 with which the conduit 60, leading to the receiver, is connected. An object of this bulb 75 is to catch any liquid or other heavier-than-air particles of matter which may have passed through the separator and to this end the bottom of the bulb is provided with an orifice 97, into which is threaded a nipple 98, having a longitudinal opening 99, which is normally closed by a rotary valve-piece 101.

Referring again to the structure of the valve mechanism disclosed in Figs. 5 to 8 85 inclusive, it should be explained that the wall of the casing 5 on the outlet side, where the separator 30 is located, is provided with a cylindrical bore into which the core 33, carrying the series of check valves, is inserted. 90 This core is held in place at its opposite ends by the heads 8 and 9 of the casing, the head 9 having a registering opening 102, whose outer portion is threaded as shown at 105, to receive a screw plug 104, which is 95 omitted in Fig. 5 but disclosed in Fig. 2. This statement is believed to be sufficiently accurate in view of the fact that this plug may be considered a part of the head with which it is connected. It should be explained, however, that the opening 102 is 100 of such size as to permit the removal of the core or valve casing 33 without removing either head, it being only necessary to detach the plug 104.

The oil receptacle 19 is provided with a gage glass 107, which is held in place by a slotted plate 108, which extends outwardly from the glass and performs the double function of holding the latter in place and protecting it from injury.

It should be mentioned that the plunger valve 64 is provided a short distance in the rear of its seating extremity with a series of openings, 115, through which the compressed 115 air passes freely on its way to the receiver when the valve is unseated, its forward extremity being then moved far enough away from its seat for the purpose, the said opening being closed against the passage of air 120 when the valve is in the closed or seated position.

It should be explained that the tube 76 for unloading the pressure in the system, functions not only when the rotor stops, but 125 also when the rotor is in motion, but running idly, as when the air inlet 100 is closed.

Each of the slidable blades 21 of the rotor is recessed at its opposite extremities to receive packing members 121, which are acted 130

on by springs 125 to maintain them in sealing relation with the end heads of the rotor chamber. These packing members 121 have a limited degree of movement in their recesses or cavities to compensate for varying conditions when the machine is in operation. They are connected with the blades by pins 123, which are passed through slots in projections 122 entering recesses 124.

- 10 As the following combination, to wit:
- 15 A chamber, a rotor eccentrically mounted therein and having an axial passage and radial slots in communication therewith at their inner extremities, blades slideable in said slots and whose outer extremities engage the inner surface of the chamber, a liquid-containing receptacle below the chamber and in communication below the level of the liquid with the said passage of the rotor and said 20 slots, the slots being the only outlet for the liquid after it enters said passage, an air and liquid separator arranged above the said receptacle and in communication with the rotor chamber on the outlet side and with the said receptacle for the return of the 25 liquid and whereby the liquid in the receptacle is under the service pressure of the air when the machine is in operation for air-compression purposes,
- 30 is common to this application and my co-pending application, Serial No. 212,539, filed January 19th, 1918, it is claimed in the last named application, and not claimed herein.

I claim:

- 35 1. In a rotary air compressor, the combination of a chamber, a rotor eccentrically mounted therein and having an axial passage and radial slots in communication therewith at their inner extremities, blades slideable in said slots and whose outer extremities engage the inner surface of the chamber, a liquid-containing receptacle below the chamber and in communication below the level of the liquid, with the said passage of the rotor, 40 an air and liquid separator arranged above the said receptacle and in communication with the rotor chamber on the outlet side and with the said receptacle for the return of the liquid, and whereby the liquid in the receptacle is under the service pressure of the air when the machine is in operation for air-compression purposes, and means for automatically relieving the liquid in the receptacle from the service pressure as soon as the 45 machine ceases to operate, or is running idly.
- 50 2. In a structure of the class described, the combination of a chamber, a rotor mounted therein and having an axial passage and radial slots in communication therewith, blades slideable in the slots, a liquid-containing receptacle below the chamber and in communication below the level of the liquid with the said passage in the rotor, an air and liquid separator arranged above the said receptacle 55 and in communication with the rotor chamber

60 ber on the outlet side and with the said receptacle for the return of the liquid and whereby the latter is under the pressure of the air in the separator when the machine is in operation, and means for automatically relieving the liquid in the receptacle from the said pressure when the machine ceases to operate, said means comprising a tube in communication at one extremity with the receptacle above the liquid, and in 65 communication with the atmosphere at its opposite extremity, and a check valve normally acted on by the rotor chamber pressure to cut off said last named communication but spring-held in the open position when 70 the rotor is inactive, or is running idly.

75 3. In a structure of the class described, the combination of a chamber, a rotor mounted therein and having a central passage extending axially thereof, radial slots communicating at their inner extremities with said passage, and blades slideable in the slots, a liquid-containing receptacle below the chamber and in communication below the level of the liquid with the said rotor passage, an air and liquid separator positioned above the said receptacle and in communication with the rotor chamber on the outlet side of the latter, and whose lower portion 80 is in communication with the said receptacle for the return of the liquid, and means for automatically relieving the liquid in the receptacle from the pressure in the separator as soon as the rotor is inactive, said means comprising a conduit in communication 85 with the said receptacle above the liquid at one extremity and in communication at its opposite extremity with the atmosphere beyond the separator, and a check valve acted on by the pressure in the separator to cut 90 off communication between the said conduit and the atmosphere when the machine is in operation but spring-held in the open position when the rotor is inactive, or is running 95 idly.

100 4. In a rotary air compressor, the combination of a chamber having an inlet for atmospheric air, and an outlet for compressed air, a rotor eccentrically mounted 105 therein and having an axial passage and radial slots in communication therewith at their inner extremities, blades slideable in said slots and whose outer extremities engage the inner surface of the chamber, a liquid-containing receptacle below the said 110 chamber, a conduit leading from said receptacle below the level of the liquid, to the axial passage of the rotor chamber, means beyond the rotor chamber outlet for separating the liquid from the compressed air, 115 a check valve for cutting off communication between the rotor chamber outlet and said means when the rotor is inactive, the separating means being in communication with the said receptacle for the return of the 120 liquid, and a conduit leading from the 125 said receptacle to the atmosphere, the 130 check valve being normally closed and spring-held in the closed position when the rotor is inactive, and being held open when the rotor is in operation.

liquid to the latter, and means for automatically relieving the liquid in the said receptacle from the pressure in the separating means when the rotor is inactive, or is running idly.

5. In a rotary air compressor, the combination of a chamber having an inlet for atmospheric air, and an outlet for compressed air, a rotor eccentrically mounted therein and having an axial passage and radial slots in communication therewith at their inner extremities, blades slidable in said slots and whose outer extremities engage the inner surface of the chamber, a liquid-containing receptacle below the said chamber, a conduit leading from said receptacle below the level of the liquid, to the axial passage of the rotor chamber, means beyond the rotor chamber outlet for separating the liquid from the compressed air, a check valve for cutting off communication between the rotor chamber outlet and said means when the rotor is inactive, the separating means being in communication with the said receptacle for the return of the liquid to the latter, means for automatically relieving the liquid in the said receptacle from the pressure in the separating means when the rotor is inactive, said last named means including a conduit in communication at one extremity with the receptacle above the liquid therein and at its opposite extremity with the atmosphere, and a check valve acted on by the pressure in the separating means for cutting off said last named communication when the machine is in operation.

6. A rotary air compressor, comprising a chamber having an inlet for atmospheric air, and an outlet for compressed air, a rotor eccentrically mounted in said chamber, a liquid containing receptacle arranged below the rotor chamber and in communication below the liquid with the said chamber, means extending beyond the compressed air outlet of the rotor for separating the liquid from the air, means for returning said liquid to the receptacle and whereby the liquid therein is under the pressure in the separating means, and means for automatically relieving the liquid in the receptacle from such pressure when the rotor is inactive, or running idly.

7. A rotary air compressor, comprising a chamber having an inlet for atmospheric air, and an outlet for compressed air, a rotor eccentrically mounted in said chamber, a liquid-containing receptacle arranged below the rotor chamber and in communication below the liquid with the said chamber, means extending beyond the compressed air outlet of the rotor for separating the liquid from the air, means for returning said liquid to the receptacle and whereby the liquid therein is under the pressure in the separating means, and means for automatically relieving

ing the liquid in the receptacle from such pressure when the rotor is inactive, said last named means including a conduit having one extremity in communication with the receptacle above the liquid and its other extremity in communication with the atmosphere, and a check valve acted on by the rotor chamber pressure for cutting off said last named communication when the machine is in operation.

8. A structure of the class described, comprising a chamber having an inlet for atmospheric air, a rotor eccentrically mounted in said chamber, a liquid-containing receptacle arranged below the rotor chamber and in communication below the liquid with the said chamber, means extending beyond the compressed air outlet of the rotor for separating the liquid from the air, a check valve between the separator and the rotor chamber outlet to cut off communication by back pressure with the rotor chamber when the rotor is inactive, means for returning said liquid to the receptacle from the separating means, and means for automatically relieving the liquid in the receptacle from the separator pressure when the rotor is inactive, or running idly.

9. A rotary air compressor, having a liquid receptacle below the rotor chamber and in communication with the latter to cause the liquid to enter and pass through the chamber by centrifugal force, means in communication with the compressed air outlet of the rotor chamber for separating the liquid from the air and returning the liquid to the receptacle under the pressure in the separator, and means for automatically relieving the liquid in the receptacle from the system pressure when the rotor is inactive, or running idly.

10. A rotary air compressor, comprising a chamber, a rotor therein, a liquid-containing receptacle below the rotor chamber, a connection between the receptacle and the chamber, whereby the liquid is caused to enter the chamber and pass out with the compressed air, means in communication with the compressed air outlet of the chamber for separating the liquid from the air and returning the liquid to the liquid receptacle, and a tube leading from the said receptacle above the liquid therein and whose outer extremity enters the rotor chamber outlet and extends in the direction of the passage of the fluid to the separator, to facilitate the circulation of the liquid through the system.

11. A rotary air compressor, whose casing is provided with an opening intersecting the fluid outlet of the rotor chamber, and a casing inserted in said opening and carrying a number of check valves, the valve casing being cored to form air passages for the fluid.

12. A rotary air compressor, whose casing is provided with an opening intersecting the fluid outlet of the rotor chamber, a casing inserted in said opening and carrying a number of check valves, the valve casing being cored to form air passages for the fluid, and means for retaining the valve casing in place.
13. A rotary air compressor, the wall of whose casing is bored to intersect the fluid outlet, and a casing inserted in said bore and carrying check valves, the said casing being cored to allow the fluid to pass through when the check valves are open.
14. A rotary air compressor, whose casing is provided with detachable heads, the wall of the casing having an opening intersecting the fluid outlet, and a casing inserted therein and carrying a check valve controlling the passage of fluid through the chamber of the valve casing, the latter being held in place by the heads of the rotor casing.
15. A rotary air compressor, having an opening in its casing extending parallel with the axis of rotation, said opening intersecting the fluid outlet, and a member inserted in said opening and carrying a number of
- check valves controlling the passage of fluid through the chamber of the valve casing.
16. A rotary air compressor, whose casing is provided with detachable heads, the wall of the casing having an opening intersecting the fluid outlet, and a casing inserted in the opening and carrying a check valve for controlling the passage of fluid through the chamber of the valve casing, the latter being cored for the purpose, and held in place by the heads of the rotor chamber.
17. A rotary air compressor, whose casing is provided with detachable heads, the wall of the casing having an opening intersecting the fluid outlet, a casing inserted in the opening and carrying a check valve for controlling the passage of fluid through the chamber of the valve casing, the latter being cored for the purpose and held in place by the heads of the rotor chamber, one of the said heads having an opening registering with the opening in which the valve casing is inserted, and a detachable closure for the opening in the said head.

In testimony whereof I affix my signature.

HENRY O. JACKSON.
